ELEVATING TRUCK HAVING PEDAL OPERATED FLUID ACTUATED LIFTING MECHANISM

Frederick J. Shepard, Jr., West Newton, and Nathaniel Warshaw, Belmont, Mass., assignors to Lewis-Shepard Company, Watertown, Mass., a corporation of Massachusetts

Application October 24, 1936, Serial No. 107,423

10 Claims. (Cl. 254—10)

This invention relates to improvements in elevating trucks which are employed for transporting heavy loads and one of the objects of the invention is to provide an elevating truck having an all-steel main frame and an all-steel load supporting means movable upwardly relatively thereto and which is so designed and fabricated that the truck may be manipulated and the load supporting means lifted in a minimum space.

10 Another object of the invention is to provide an elevating truck of the character described with load supporting means having an integral hollow upwardly extending standard in the form of a hood adapted to protect the lifting mechanism for raising the load supporting means.

Another object of the invention is to provide a fluid actuated jack having a vertical cylinder and ram located within the chamber of the standard and preferably operated by pedal mechanism in which uniform foot pressure is applied for every stroke.

Another object of the invention is to provide an elevating truck in which the load supporting means is mounted by parallel links upon the main frame with a vertical fluid actuated jack pivotally mounted thereon and having its ram pivotally connected to the upper portion of the standard, with means for actuating the pump plunger to raise the load supporting means, and means for releasing fluid from the ram cylinder including an outlet valve with manually operated means mounted upon the standard and so connected to the outlet valve as to permit controlled actuation of the outlet valve irrespective of the position of the load supporting means.

Another object of the invention is to provide a novel and efficient fluid actuated jack pivotally connected at its respective ends to the main frame and the standard with pedal actuated means for operating the pump plunger and comprising means which will insure application of the force applied to the pump plunger accurately in the direction of the axis of the pump plunger.

Another object of the invention is to provide novel means for holding the tongue in upraised position and operable to swing the tongue to upraised position when the tongue, after having been depressed, to steering position, is released.

These and other objects and features of the invention will more fully appear from the following description and the accompanying drawings and will be particularly pointed out in the claims.

In the drawings.

Fig. 1 is a side elevation of an elevating truck embodying the preferred form of the invention;

showing the load supporting means in elevated position and indicating in dotted lines its lowered position;

Fig. 1—*a* is a front view of the main frame of the steering mechanism;

Fig. 2 is a front elevation, the forward portion of the head of the steering mechanism being broken away to illustrate more clearly the fluid actuated jack and mechanism for operating the same;

Fig. 3 is a horizontal sectional view of the standard on lines 3—3 Fig. 2;

Fig. 4 is a plan view of the construction illustrated in Fig. 1;

Fig. 5 is a vertical sectional view of the fluid actuated jack construction on the broken lines 5—5 Fig. 6;

Fig. 6 is a horizontal sectional view on lines 6—6 Fig. 5; and,

Fig. 7 is a detail sectional view on lines 7—7 Fig. 6, viewed from the right toward the left.

In the preferred construction illustrated in the accompanying drawings the main frame is of an all-steel assembly fabricated from sheet steel plates and bars welded together to provide an integral unit. The head comprises a horizontal box-like construction having a top 1, and front and rear walls 2 and 3, and a bottom wall 4 formed of steel plates welded together. The top plate 1 is provided with downwardly and laterally extending flanges 5 and other flanges 6 spaced apart from and located in parallelism with and in proximity to the outer flanges 5 are welded to the bottom plate 4 of the box, thereby providing downwardly chambered end portions so separated as to provide a space for the steering mechanism beneath the central portion of the box-like structure.

The box-like structure is provided centrally with a vertical sleeve which forms a bearing for a hollow steering post 8 which is provided at its lower end with a forked steering head comprising an upper flat plate 9 parallel to the bottom plate 4 of the box-like structure, with a downwardly extending fork 10 having mounted in its lower end a shaft 11 upon which the wheels 12 of the steering mechanism are journaled. Suitable anti-friction bearings (not shown) desirably are interposed between the bottom plate 4 of the head and the plate 9 of the steering head, and the wheels 12 desirably are provided with anti-friction bearings to facilitate the manipulation of the steering mechanism and to decrease the power required to pull the truck.

A split collar 13, which is clamped upon the

upper end of the steering post by a bolt 14, has a pair of upwardly and forwardly extending ears 15 in the front end of which is mounted a pin 16 which forms a fulcrum for a vertically swinging tongue. The tongue comprises a handle member 17 the lower end of which is seated in a socket in a casting 18, the lower end of which is provided with parallel extensions 19 which project over the axis of the steering post and have chamfered ends which when the tongue is in raised position engages the top of the collar 13.

It is desired normally to maintain the tongue in upraised or substantially vertical position in order that the truck may occupy a minimum amount of space. One of the features of the invention comprises means for maintaining the tongue in upraised position so located that it will occupy a minimum of space and to be protected from injury. This is accomplished in the present invention by providing a spiral spring 20 which is located within the tubular steering post and secured at its lower end to a pin 21 extending diametrically through the steering post. The upper end of the spring extends between the rearward extensions 19 of the tongue and is fastened to a pin 22 which is mounted in the extensions 19.

The body of the truck comprises side frames each preferably consisting of two parallel bars 23 and 24 which are welded at their front ends respectively to the downwardly extending flanges 5 and 6 and integrally connected at their front ends by a transverse bar 25. The rear ends of the side bars 23 and 24 are provided with relatively wide downwardly extending portions 26 and the shafts 27 for the rear wheels 28 are journaled in the lower portions of such extensions. Preferably the wheels have antifriction bearings (not shown). The diameter of the rear wheels is such that their peripheries lie beneath the plane of the upper surface of the side bars and by being journaled in the lower portions of the downward extensions the body of the truck is given sufficient underclearance to enable it readily to pass over sills and the angles of juxtaposed surfaces of a floor and ramp.

One of the main features of the invention consists in providing a load supporting means of exceedingly rigid all-steel construction adapted when in lowered position to have its upper horizontal plane substantially coincident with the horizontal upper plane of the side bars of the main frame.

In the preferred construction illustrated the load supporting means which has an open rear end comprises side frames formed of pairs of parallel bars 29 and 30 integrally connected at their rear ends by a transverse member 31 having a central forwardly extending web 32. A shaft 33, which is journaled in the front end of the forward extension 32 and in the side bars 29 and 30, forms a pivot for the rear pair of parallel links 34, the lower ends of which are pivotally mounted upon the shafts 27 upon which the rear wheels are mounted.

In order to limit the downward movement of the load supporting means, lugs 35, which are welded to the inner faces of the side bars 29 and 30, are so positioned as to engage the links 34 when the upper plane of the load supporting means is substantially coincident with the upper plane of the main frame, (see Fig. 1.) The front end of the side frame members or bars 29 are integrally secured by welding to a hollow standard fabricated from steel plates and so con-

structed as to provide a hood for the lifting mechanism which will protect the lifting mechanism from injury and which also will minimize the collection of dust upon the lifting mechanism.

In the preferred construction the standard comprises wide sheet metal end plates 36, the lower ends of which are welded to the side bars 29 of the load supporting means and extend vertically upwardly therefrom a short distance and then preferably converge inwardly. A back plate 37, which is integral with the end plates, extends over the top of the standard and downwardly into proximity to the side frames. A relatively thick plate 38, which extends across the side frames, is welded to the edges of the end plates and to the back plate and preferably has a downward central extension which projects between and is welded to the inner edges of the side frames 29 and 30. The standard is also provided with a vertical front plate 39 which is formed integral with or welded to the end plates 36 and is provided with a recess having at its upper end an arcuate edge 40 with vertical edges 41 extending downwardly therefrom and terminating a sufficient distance from the lower ends of the end plates to avoid interference with the lowering of the truck. The standard is also provided with vertical inner end plates 42 which are integral with or welded to the front and rear plates and which at their upper ends lie closely adjacent to 30 or in contact with the upper ends of the outer end plates 36, thereby providing hollow uprights of great strength and rigidity. Inwardly extending bosses 43, which are welded to the inner faces of the outer end plates 36, provide sockets for 35 shafts 44 which are also mounted in the lower ends of the vertical plates 42 and form pivots for the upper ends of a pair of links 45 which are parallel to the links 34.

The upper ends of the links 45 desirably are 40 provided with bosses 46 which abut against the inner ends of the bosses 43 and the lower ends of the links 45 are provided with bosses 47 which are journaled upon shafts 48 which are mounted in the flanges 5 and 6 which are integral with 45 and extend rearwardly from the head of the truck as previously described. The inner flanges 6 desirably have welded to them bosses 49 which form additional bearing surfaces or journals for the shaft 48. By virtue of this construction a very 50 rigid mounting is provided for the front pair of the parallel links which connect the load supporting means to the main frame.

Suitable lifting mechanism which is mounted upon the main frame and acts upon the upper 55 end portion of the standard serves to raise the load supporting means and move it forwardly as it is lifted. In the preferred construction illustrated the lifting mechanism comprises a fluid actuated jack the lower end of which is pivotally 60 mounted upon the main frame and the ram of the jack pivotally connected to a shaft which is mounted in the upper end portion of the standard, the pump of the jack preferably being reciprocated by pedal mechanism.

As illustrated in the accompanying drawings the lifting jack comprises a base block 50 which is secured to a bracket 51 the lower end of which is pivotally mounted upon a shaft 52 which is supported at its ends in ears 53 of brackets 54 70 which are mounted upon the cross bar 25 of the main frame. The base block 50 has a central bore 55 provided with a screw threaded wall which receives the lower end of the vertical cylinder 56 of the fluid actuated mechanism.

The reservoir for fluid comprises a cylinder 57 which preferably is concentric with the cylinder 56 and tightly fits at its lower end upon the outer surface of a boss 58 extending upwardly from the base block 50. The fitting at the upper end of the reservoir may be loosely mounted so as to permit access of air for atmospheric pressure on the fluid in the reservoir, or this atmospheric pressure may be provided in any desired manner.

10 The base block also is provided at a suitable distance from the cylinder with another bore having a screw threaded wall which receives the screw threaded lower end of a vertical pump cylinder 59. A pump plunger 60 is reciprocably mounted in the pump cylinder and is provided at its lower end with a screw threaded extension presenting a shoulder and a piston packing 61 is clamped against the end of the shoulder by suitable nuts upon the extension. The upper end 20 of the pump cylinder is provided with a suitable stuffing box 62 and the upper end of the pump plunger is screw threaded and engaged by a fork or clevis 63 adapted to be attached to an actuating mechanism.

25 As illustrated in Figs. 5 and 6 the ram comprises a ram shaft 64 which fits tightly but slidably in the cylinder 56 and has secured to its upper end a head 65 which is pivotally mounted upon a horizontal shaft 66 which extends across the upper end of the head and is mounted in bearing sleeves 67, the ends of which extend through and are welded to the end plates 36 and 42 of the box-like uprights of the standards. The sleeves 67 desirably are reenforced by a cross bar 30 67a which is welded to both of the sleeves and also to the top plate of the standard.

The upper end of the ram cylinder 56 is screw threaded and has mounted upon it a cylindrical sleeve 68 having a central recess provided with an internally screw threaded wall complementary to the screw threads upon the upper end of the cylinder and is provided with a web which fits the ram shaft 64. The sleeve 68 is bored from its upper end to provide a chamber 69 which receives a suitable chevron packing formed of a plurality of annular packing rings 70 V-shaped in cross section and superimposed upon each other with an annular ring 71 therebeneath having a V-shaped upper surface complementary to 50 but of somewhat wider angle than those of the V-shaped packing rings. The upper end of the sleeve 68 is counterbored and internally screw threaded to receive an externally screw threaded nut 72 having a V-shaped under surface adapted 55 to engage the uppermost of the V-shaped rings of the chevron packing. The upper end of the sleeve 68 is externally screw threaded and is engaged by an internally screw threaded downwardly extending flange on a cap 73 having a 60 peripheral flange which engages the upper end of the cylindrical reservoir wall 57 and serves to clamp the reservoir wall firmly upon the shoulder of the base plate surrounding the annular boss 58.

65 The upper portion of the cap is counterbored and internally screw threaded to receive a packing and a clamping nut 14 which closely fits the ram shaft thereby providing a stuffing box construction effective to guide the ram shaft to 70 prevent escape of fluid.

In order to limit the upward movement of the ram shaft to a position safely within the ram cylinder and also to determine the limit of upward movement of the load supporting means, 75 means are provided for releasing fluid under

pressure from the ram cylinder when the ram has reached a predetermined height. In the construction illustrated the nut 72 is provided intermediate of its length with an annular groove 75 having radial outlets which communicate with vertical bores 76 leading to a space between the cap and the nut 72 which communicates with radial bores 77 in the cap 73 through which the fluid may be discharged into the reservoir. The ram shaft 64 is provided with a vertical bore 78 extending upwardly from its lower end to a predetermined height, with a port 79 extending therefrom through the wall of the ram and adapted when registering with the groove 75 to discharge fluid under pressure into it. So long as the port 79 registers with the groove 75 fluid will pass from the ram cylinder through it and the vertical bores 76 into the space between the nut and lower face of the cap and will be discharged through the outlet 77 into the reservoir. Upon cessation of reciprocation of the pump cylinder the ram shaft will lower slightly until the port 79 is out of registry with the groove 75 and the ram shaft and ram will then be sustained in upraised position by the fluid which is trapped in the cylinder beneath the ram shaft.

Inasmuch as the load supporting means is directly connected to the ram the load supporting means will be maintained at its highest elevation. The bores 76 in the nut 72 also serve to receive 30 the projections of a spanner wrench for manipulating the nut.

Suitable means are provided for drawing fluid from the reservoir to the pump and upon actuation of the pump cylinder for forcing it under pressure into the lower portion of the ram cylinder. In the construction illustrated the base block 50 is provided with an arcuate recess 80 which communicates with one end of a horizontal bore 81 the opposite end of which communicates with a vertical bore 82 leading to a transverse bore 83 which communicates with a vertical bore 84 leading to the lower end of the pump cylinder. The bore 82 is countersunk to provide a valve seat 85 for a ball valve 86 and an upper enlarged countersunk portion of the bore 82 has mounted in it a screw threaded plug 87 the lower end of which is located slightly above the ball so as to permit the ball to be raised when fluid is drawn from the reservoir through the bores 81, 82, 83, 50 and 84 by the upward or suction movement of the pump plunger. Upon discontinuance of the upward movement of the plunger the ball 86 will drop to its seat and prevent retrograde movement of the fluid when the pump plunger is forced downwardly.

The bore 84, which communicates with the lower end of the pump, also communicates with a transverse bore 88 which is plugged at its outer end and communicates intermediate of its ends 60 with a short vertical bore 89 which in turn communicates with a bore 90 leading to a vertical bore 91 extending downwardly from the bottom of the ram cylinder. The vertical bore 89 is countersunk to provide a seat for a ball valve 92 65 which is normally held seated by a spring 93 the upper end of which is engaged by a screw threaded plug 94 seated in an enlarged countersink of the bore 89.

Upon depression of the pump plunger the fluid is forced through the bores 84, 88 and 89, thereby raising the ball valve 92 so that fluid is forced through the conduits 90 and 91 into the lower end of the ram cylinder thereby raising the ram. When the fluid is forced in this direction the ball 73

valve 92 is raised, but immediately upon cessation of depression of the pump plunger the valve 92 is quickly seated by gravity and by the action of the spring 93, thereby preventing the return of any fluid from the pump cylinder to the pump.

In order to prevent clogging of the conduits for the fluid an annular screen 95 is located in the recess between the ram cylinder and the flange 58 and a similar screen 96 is located in the 10 countesink in the base below the end of the pump cylinder. It will therefore be obvious that by reciprocation of the pump cylinder, the ram shaft and ram will be raised progressively as the pump plunger is reciprocated and that the ram will 15 be retained at each step of elevation by the column of fluid trapped between the lower end of the ram shaft and the bottom of the ram cylinder.

Inasmuch as the load supporting means is 20 moved forwardly as it is raised by the ram of the fluid jack special means are provided for reciprocating the pump plunger in the direction of its axis. In the particular construction illustrated a pair of links 97 are pivoted at their lower ends upon 25 a shaft 98 which is mounted in a sleeve 99 welded to the bracket 51. The links 97 desirably are connected by a web 100 to insure uniformity of movement. A shaft 101 is mounted in the upper ends of the links 97 and has pivoted upon 30 it a cylindrical rocker 102 having near one end, its right end Fig. 2, two forwardly projecting arms 103 and 104. The end portion of the arm 103 is pivotally connected to the clevis 63 upon the upper end of the pump plunger 60. The front end 35 of the arm 104 is pivotally connected to a clevis 105 upon the upper end of a rod 106 the lower end of which is provided with a clevis 107 which is pivotally connected to an arm 108 which is fixedly secured to one end of a shaft 109 which is 40 mounted in suitable bearings in the flanges 5 and 6 of the main frame. The other end of the shaft 109 has fixedly secured to it a pedal 110. It is therefore obvious that upon depression of the 45 pedal 110 the rod 106 may be drawn downwardly, thereby rocking the arms 104 and 103 downwardly and forcing the pump plunger 60 downwardly so that fluid under pressure will be forced into the ram cylinder.

Means are provided for raising the pump 50 plunger and restoring the pedal to upraised position. In the particular construction illustrated the rocker sleeve 102 is provided with another forwardly extending arm 111 to which is pivotally connected a clevis 112 upon the upper end of a 55 guide rod 113, the lower end of which extends through a suitable hole in a flange 114 projecting from the bracket 51. A compression spring 115 which encircles the rod 113 is seated at its lower end upon the extension 116 of the bracket and 60 abuts at its upper end against a shoulder upon the clevis 112, serves normally to hold the pump plunger in raised position and also to hold the pedal in upraised position. When the pedal is forced downwardly the spring 115 is compressed 65 and upon release of the pedal expands and restores the members to upraised position.

In order to permit the descent of the load supporting means, it is desirable to provide conveniently located manually operable mechanism for 70 permitting fluid under pressure to flow from the ram cylinder to the reservoir and such manually operable releasing mechanism desirably is mounted upon the standard. Inasmuch, however, as the load supporting means and standard, are moved forwardly and rearwardly as the load sup-

porting means is raised and lowered, flexible means are provided for actuating the outlet valve which controls the escape of fluid from the ram cylinder to the reservoir.

In the preferred construction illustrated a 5 conduit 116 leads from the vertical bore 91 which communicates with the lower portion of the cylinder beneath the screen 96 to a vertical bore or port 117 which communicates with a conduit 118 which in turn communicates with the lower portion of the reservoir through the screen 95. The base block 50 is provided with a vertical bore in axial alinement with the port or bore 117 to receive the stem 119 of a needle valve, the lower end of which is reduced in diameter and tapered to provide a valve fitting a complementary seat in the upper end of the port 117. The valve stem 119 has an enlarged screw threaded portion 120 which engages complementary internal threads in a nut 121 which is externally screw threaded to 20 engage complementary screw threads in the wall of a countersink in said base block. The countersink is of sufficient depth to receive a suitable packing 122 thereby providing a stuffing box for the valve stem which will prevent escape of the 25 liquid under pressure which is forced from the ram cylinder into the reservoir upon raising of the valve. The valve stem 120 has secured to its upper end a clevis 123 which is pivotally connected to a complementary clevis 124 upon the lower end 30 of a rod 125 of square or other angular cross section which fits and is slidably mounted in a complementary channel in a sleeve 126. The upper end of the sleeve 126 is connected to a rod 127 which is journaled in the top plate of the 35 standard. The upper end of the rod 127 is fixedly secured to a hollow cylindrical head 128 having a horizontally extending arm 129. A spring 130, which encircles the rod 127 and is secured at its upper end to the head 128 and at its lower end 40 to the upper plate of the standard, tends to rotate the rod 127 in a direction to screw the needle valve downwardly and thereby close the outlet port 117.

When it is desired to release the fluid under 45 pressure from the ram cylinder to permit descent of the load supporting means, the arm or handle 129 is turned in a direction to unscrew the screw 50 threaded portion 120 of the valve stem from the nut 121, thereby gradually raising the valve and permitting the fluid to flow from the ram cylinder into the reservoir. If the operator should release the handle at any time the spring 130 will rotate the valve stem in a direction to restore 55 the valve to seated position, thereby preventing any uncontrolled descent of the load supporting means.

In the operation of the truck the valve-operating lever 129 is first rotated to a position to 60 permit descent of the load supporting means until the upper plane of the side frames substantially coincides with the upper plane of the main frame. The truck may then be backed beneath the skid or article to be transported and when properly located the platform may be raised by 65 repeated depressions of the foot lever, thereby causing the ram to raise the standard and the load supporting means which is integral with it and at the same time move the load supporting means forward. The load supporting means may 70 be thus raised to any desired position and it will be held in such position by the fluid which is trapped in the ram cylinder beneath the ram shaft. The fluid actuated jack may be so constructed that the load can be raised to any de- 75

sired height sufficient to insure the legs of the skid, or of the article being raised, to clear the floor or any other obstructions and the under-clearance of the frame is such that the truck can be drawn over sills or over abrupt angles in the ramp without engagement therewith.

When the truck has reached its destination the load supporting means may be lowered by manipulation of the handle lever as described so that the load will be deposited gently and without shock.

It will be understood that the preferred embodiment of the invention disclosed herein is of an illustrative character and is not restrictive, and that various changes may be made in form, construction and arrangement of parts within the meaning and scope of the following claims.

Having thus described the invention, what is claimed as new, and desired to be secured by Letters Patent, is:

1. An all steel elevating truck having a wheel-supported integral main frame comprising a horizontal hollow rectangular head having pairs of downwardly extending flanges providing between the inner flanges a space for the steering mechanism, steering mechanism mounted in said head, side frames formed of pairs of parallel bars integrally connected to the respective downwardly extending flanges of said head and extending rearwardly therefrom, wheels mounted between the rear ends of the respective pairs of side bars, load supporting means having parallel pairs of side bars arranged telescopically to fit over and lie no higher than the side bars of the main frame when the load supporting means is in lowered position mounted by parallel links upon said main frame, and means for raising said load supporting means upwardly relatively to said main frame.

2. An all steel elevating truck having a wheel-supported integral main frame comprising a horizontal hollow rectangular head having pairs of downwardly extending flanges providing between the inner flanges a space for the steering mechanism, side frames formed of pairs of parallel bars integrally connected to the downwardly extending flanges of said head and extending rearwardly therefrom and provided at their ends with downwardly extending wider portions, wheels having axles mounted in said downward extensions and having such diameter that the periphery of the wheels will lie below the horizontal plane of the upper edge of the side frames, load supporting means having side frames arranged telescopically to fit over the side frames of the main frame when the load supporting means is in lowered position, thereby to permit the load supporting means to be lowered until the upper horizontal plane of the load supporting means is substantially coincident with the upper plane of the side frames, and front and rear pairs of parallel links connecting said frame to said load supporting means, the rear pairs of links being pivotally mounted upon the axles of the rear wheels.

3. An all steel elevating truck having a wheel-supported main frame, load supporting means mounted upon and movable upwardly relatively to said main frame comprising side frames and a hollow standard welded thereto formed of pairs of upwardly extending end plates welded to said side frames and front and back plates welded to the respective front and rear edges of the end plates and extending across the upper ends thereof, a fluid actuated jack for raising said

load supporting means pivotally mounted upon said main frame and located within the chamber of said standard and comprising a reservoir, a vertical ram cylinder, ram and pump, means for actuating the pump plunger, to supply fluid under pressure to said ram cylinder, an outlet conduit leading from said ram cylinder to said reservoir, a valve for said conduit having a screw threaded stem operable when rotated in one direction to close said conduit and when rotated in the other direction gradually to open said conduit, and means for rotating said valve comprising a handle member mounted on said standard and extensible means connecting said handle member to said valve stem adapted to permit operation of the valve irrespective of the height to which the load supporting means is raised.

4. An all steel elevating truck having a wheel-supported main frame, load supporting means mounted upon and movable upwardly relatively to said main frame comprising side frames and a hollow standard formed of upwardly extending end plates welded to said side frames and front and back plates welded to the respective front and rear edges of the end plates and extending across the upper ends thereof, a fluid actuated jack for raising said load supporting means pivotally mounted upon said main frame and located within the chamber of said standard and comprising a reservoir, a vertical ram cylinder, ram and pump, means for actuating the pump plunger to supply fluid under pressure from said reservoir to said ram cylinder, an outlet conduit leading from said cylinder to said reservoir, a valve for said conduit having a screw threaded stem operable when rotated in one direction to close said conduit and when rotated in the other direction gradually to open said conduit, an upwardly extending bar of angular cross section pivotally connected to said valve stem, a handle member rotatably mounted in said standard having a sleeve provided with a longitudinal channel of angular cross section complementary to that of said bar telescopically mounted on said bar and operable to rotate said valve irrespective of the height to which the load supporting means is raised.

5. An all steel elevating truck having a wheel-supported main frame, load supporting means mounted upon and movable upwardly relatively to said main frame comprising side frames and a hollow standard formed of upwardly extending end plates welded to said side frames and front and back plates welded to the respective front and rear edges of the end plates and extending across the upper ends thereof, a fluid actuated jack for raising said load supporting means pivotally mounted upon said main frame and located within the chamber of said standard and comprising a reservoir, a vertical ram cylinder, ram and pump, means for actuating the pump plunger to supply fluid under pressure from said reservoir to said ram cylinder, an outlet conduit leading from said cylinder to said reservoir, a valve for said conduit having a screw threaded stem operable when rotated in one direction to close said conduit and when rotated in the other direction gradually to open said conduit, means for rotating said valve comprising a handle member mounted on said standard and extensible means connecting said handle member to said valve stem adapted to permit operation of the valve irrespective of the height to which the load supporting means is raised, and a spring acting

- on said valve stem in a direction to cause the valve to close said outlet conduit.
6. An all steel elevating truck having a wheel-supported main frame, load supporting means mounted upon and movable longitudinally of and upwardly relatively to said main frame, a fluid operated jack having a base pivotally mounted upon the main frame and comprising a reservoir, a vertical ram cylinder and ram and a pump for forcing fluid from said reservoir into said ram cylinder, means pivotally connecting the ram to said load supporting means to permit longitudinal movement of said load supporting means, mechanism for actuating the plunger of said pump comprising parallel connected pump links pivotally mounted upon a shaft in the base of said jack and extending upwardly therefrom, a horizontal shaft mounted in the upper end of said links, a rocker mounted upon said upper shaft having forwardly extending arms one of which is connected to the pump plunger and another of which is connected by a link to a pedal actuated lever.
7. An all steel elevating truck having a wheel-supported main frame, load supporting means mounted upon and movable longitudinally of and upwardly relatively to said main frame, a fluid operated jack having a base pivotally mounted upon the main frame comprising a reservoir, a vertical ram cylinder and ram and a pump for forcing fluid from said reservoir into said ram cylinder, means pivotally connecting the ram to said load supporting means to permit longitudinal movement of said load supporting means, mechanism for actuating the plunger of said pump comprising parallel connected pump links pivotally mounted upon a shaft in the base of said jack and extending upwardly therefrom, a horizontal shaft mounted in the upper end of said links, a rocker mounted upon said upper shaft having forwardly extending arms one of which is connected to the pump plunger and another of which is connected by a link to a pedal actuated lever, and means for lifting said pump plunger comprising another forwardly extending arm of said rock shaft having connected thereto a vertical rod, a guide in the base of said jack for said rod and a compression spring encircling said rod having its lower end resting upon said guide and its upper end engaging a shoulder on said rod and operable upon release of downward pressure upon said pedal actuated lever to raise it and thereby to raise said pump plunger.
8. An all steel elevating truck having a wheel-supported main frame and load supporting means movable longitudinally and upwardly relatively to said main frame and having an integral upwardly extending standard, means for raising said load supporting means comprising a fluid operated lifting jack having a base block mounted on said main frame, a cylinder and a pump extending vertically upwardly from said base, a ram shaft closely fitting and reciprocable in said cyl-

inder and pivotally connected to said standard, a tubular reservoir enclosing said cylinder having at its upper end a head closing the upper end of said reservoir and having a base detachably secured to said cylinder by screw threaded connection and provided with a stuffing box having a chevron packing tightly embracing said ram shaft and effectively closing the upper end of said cylinder against the passage of fluid along the ram shaft, and conduits having suitable check valves for conducting fluid from said reservoir to said pump and upon actuation of said pump to conduct fluid under pressure from said pump to said cylinder to raise said ram, and means for actuating said pump plunger means for releasing fluid from said ram cylinder including a conduit leading from said cylinder to said reservoir, a valve in said conduit and a jointed extensible rod mounted in said standard and connected to said valve.

9. An elevating truck having a wheel-supported main frame having a head at its front end, steering mechanism having a vertical tubular steering post mounted in said head, a tongue pivotally mounted upon said steering post having an extension projecting across the vertical axis of the steering post, a spiral spring connected to said tongue extension located within said tubular steering post and having its lower end rigidly connected to said steering post acting normally to maintain said tongue in upraised position.

10. An all steel elevating truck having a wheel-supported main frame comprising a head having steering mechanism mounted thereon, a horizontal side frames integral with and extending rearwardly from said head and provided with downwardly extending offset rear end portions, rear wheels having an axle mounted in said extensions, said wheels being of such diameter as not to extend above the horizontal plane of the upper surface of said side frames, in which the axle of the rear wheels is mounted to provide ample underclearance for the truck, load supporting means having a standard and side bars integral therewith and extending rearwardly therefrom adapted to telescope over the side bars of said frame and of such vertical width that when in lowered position the horizontal plane of the upper surfaces of said side bars will be substantially coincident with the horizontal plane of the upper edges of the side frames, parallel links connecting the load supporting means to the frame comprising a front pair of links and a rear pair of links mounted on the axle of said rear wheels, means for raising and for lowering said load supporting means, and bosses on said load supporting means so positioned as to engage the rear pair of links when the load supporting means is lowered and to arrest further descent of the load supporting means when the horizontal planes of the upper surfaces of the load supporting means and frame are substantially coincident.
